ATTORNEY

UNITED STATES PATENT OFFICE.

ROBERT P. GREEN, OF COLUMBUS, OHIO.

TELEPHONE-TRANSMITTER.

SPECIFICATION forming part of Letters Patent No. 567,132, dated September 8, 1896.

Application filed May 31, 1895. Renewed February 12, 1896. Serial No. 579,103. (No model.)

To all whom it may concern:

Be it known that I, ROBERT P. GREEN, a citizen of the United States, residing at Columbus, in the county of Franklin and State 5 of Ohio, have invented a certain new and useful Improvement in Telephone-Transmitters, of which the following is a specification.

My invention relates to the improvement of telephone-transmitters; and the objects of 10 my invention are to provide a transmitter of this class of superior construction and arrangement of parts, to construct the same in a simple, inexpensive, and effective manner, and to produce other improvements in details 15 of construction and arrangement of parts, which will be more fully pointed out hereinafter. These objects I accomplish in the manner illustrated in the accompanying drawings, in which—

20 Figure 1 represents a central vertical section of my improved transmitter. Fig. 2 is an enlarged central vertical sectional view of the inner or secondary diaphragm; and Fig. 3 is a view in elevation of said secondary dia- 25 phragm, showing one of the face-plates removed therefrom.

Similar letters refer to similar parts throughout the several views.

In the construction of my device I employ 30 an outer or main diaphragm *a*, of thin sheet metal or other suitable material, the latter being secured over the enlarged mouth portion *b* of a recess *b'*, formed in a suitable transmitter-block *c*, of non-conducting mate- 35 rial.

The main diaphragm-plate *a* has extending from its center and projecting into the recess *b'* a metallic stem *d*. To the inner end of this stem *d* is secured the central portion of the 40 metallic backing-plate *d'* of the inner or sec- ondary diaphragm *d''*. In constructing the secondary diaphragm I secure to the inner face of said plate *d'*, adjacent to its edge portions, a frame or gasket *e*, preferably formed 45 of paper or pasteboard, but which may be formed of any suitable non-conducting mate- rial. In this manner a shallow cup or recess is formed within said frame, which said space 50 I fill with granular sulfid of copper or other suitable conducting substance *e'*. Over the

open side of the receptacle or cup formed as above described I secure a metallic plate *f*, corresponding with the plate *d'*.

g and *g'* represent, respectively, the battery-wires, one of which leads from the plate *f* 55 and the remaining one of which leads from the main diaphragm *a*. Over the outer face of the main diaphragm and against the block *c* I secure a suitable mouthpiece *h*.

In operation the voice vibrations or sound-waves are transmitted from the main dia- 60 phragm through the stem or pin *d* and back- ing-plate *d'*. Through the medium of the granular-conducting substance *e'* the vibra- 65 tions or sound-waves are conveyed to the plate *f* and thence off through the line-wire *g*.

Although I have shown and described herein 70 a form of mouthpiece and transmitter frame- block, it is evident that these parts may be changed or altered as desired without affect- ing my invention.

What I claim, and desire to secure by Let- 75 ters Patent, is—

1. In a telephone-transmitter the combina- 75 tion of the main diaphragm *a*, a conducting- pin secured to and projecting from said main diaphragm, an inner or secondary diaphragm consisting of two conducting-plates the inner faces of said plates being separated by a frame 80 of non-conducting material, a filling of granu- lar conducting substance between said plates, a wire leading from the secondary diaphragm, and a wire leading from the main diaphragm, substantially as and for the purpose specified.

2. In a telephone-transmitter the combina- 85 tion with a main diaphragm, a mouthpiece in front of the same and a pin projecting in- ward from said main diaphragm opposite said mouthpiece-opening, of an inner or sec- ondary diaphragm consisting of two conducting- 90 plates *d'* and *f*, a filling of granular sulfid of copper between said plates, one of said plates being secured to and supported from the pin *d* and wires *g* *g'* leading respectively from the main and secondary diaphragms, sub- 95 stantially as and for the purpose specified.

ROBERT P. GREEN.

In presence of—

C. C. SHEPHERD,
A. L. PHELPS.
